UNITED STATES PATENT OFFICE.

WILLIAM F. ZIMMERMANN, OF WAVERLY, NEW YORK, ASSIGNOR TO INGERSOLL-RAND COMPANY, OF JERSEY CITY, NEW JERSEY, A CORPORATION OF NEW JERSEY.

PNEUMATIC CHIPPING HAMMER.

Application filed March 27, 1925. Serial No. 18,656.

This invention relates to pneumatic hammers, but more particularly to high speed pneumatic chipping hammers for steel casting and billet work, especially designed for cleaning and chipping steel castings and for scaling and chipping high carbon and alloy steel billets.

The objects of the invention are in general to enable a high speed hammer to be constructed in a simple and rugged manner which insures long life; make the hammer easier to hold in which the high speed enters as an important factor, obtain good balance and enable the operator to readily control the force of the blows of the hammer piston.

Further important objects are to improve upon the construction and operation of the distributing valve, and render the valve more sensitive and at the same time more dependable and uniform in its action especially at high speeds.

Additional objects of the invention will hereinafter appear and to all of these ends the invention consists of the features of construction, combinations of elements and arrangement of parts, having the general mode of operation as hereinafter more fully described and claimed, and shown in the accompanying drawings, illustrating one preferred form of the invention, in which,

Figure 1 is a sectional elevation of the chipping hammer,

Figure 2 is a detail perspective view in transverse section of the forward valve box cap,

Figure 3 is a similar view of the valve box,

Figure 4 is a similar view of the rearward valve box cap and exhaust deflector,

Figure 5 is an enlarged detail longitudinal sectional elevation partly broken away of the valve and valve box assembly,

Figure 6 is a perspective view of the exhaust deflector,

Figure 7 is a conventional longitudinal sectional elevation partly broken away of the cylinder and valve assembly showing the distribution of the pressure fluid, and

Figure 8 is a view similar to Figure 7 with the valve in another position.

Referring to the drawings, the cylinder or barrel A is formed with the bore B for the reciprocating hammer piston C having the neck D. Blows of impact are imparted to

the chisel or tool E located at the front end of the cylinder. The rearward portion of the cylinder is provided with an enlarged bore F to receive the valve box G in the form of a hollow block, and also to receive the forward valve box cap H and the rearward valve box cap J. The valve box and the two caps together form a complete valve chest or cage. The handle K having the handle grip L forms the back head of the chipping hammer and is suitably secured to the barrel as by means of the bolts O. The handle grip contains the throttle valve (not shown) controlled by the latch P for supplying pressure fluid to the machine.

The pressure fluid actuated distribution valve Q is preferably of the differential type and is located in the valve box G with its axis longitudinal. Pressure fluid is supplied to the machine from the supply passage R in the handle L and a main free exhaust S is provided for the machine at a point located rearwardly of the valve. This main exhaust is conveniently located in the rearward valve box cap J and an exhaust deflector T is provided for this main exhaust between the handle and cylinder.

In accordance with this invention, the supply of pressure fluid to both ends of the cylinder is controlled by the valve, and the main free exhaust from the forward end of the cylinder through the exhaust passage U is controlled only by the piston C, and in addition to this main exhaust an auxiliary exhaust is provided from the front end of the cylinder through the passage V controlled only by the valve Q. The exhaust from the rear end of the cylinder through the port W passes through the valve Q itself to the main exhaust S and is controlled only by the valve.

The valve is thrown forward and held in forward position by live fluid pressure acting upon the shoulder of the enlarged head of the valve, and the valve is thrown to rearward position and held in said position by live pressure fluid acting against the valve in a rearward direction and controlled by the neck D of the piston which cooperates with the passage X in the cylinder.

The differential valve Q is preferably formed with the enlarged head Y and the neck Z, and the valve has an open rearward end a. The enlarged head Y forms a rearward shoulder b on the valve having a for-

wardly acting pressure surface and the pressure of the live fluid upon this surface *b* actuates the valve forwardly and holds the valve in forward position as indicated in Figures 5 and 7, for instance, because the pressure fluid supplied through the passage *R* in the handle passes directly to the valve around the neck *Z*, and from thence to the rearward end of the cylinder through the ports and passages indicated for driving the piston forwardly. The rearwardly acting pressure surface *c* of the enlarged head of the valve is subjected to atmospheric pressure when the valve is in its forward position as indicated in Figure 7 through the passage *X* and the exhaust passage *U* and the passage *V*. When live pressure fluid is supplied through the passage *T'* in the cylinder and around the neck *D* of the piston and through the passage *X* to the rearwardly acting pressure surface *c* of the valve as indicated in Figure 8, the valve will be actuated rearwardly and held in rearward position owing to the fact that the area *c* is larger than the area *b*.

In the operation of the chipping hammer, let it be assumed that the piston is in its rearmost position as indicated in Figure 7 and the valve is in its forward position in which case live pressure fluid admitted from the passage *R* in the handle will pass through the rearward valve box cap *J* and through passages in the valve box around the neck *Z* of the valve and through a passage in the forward valve box cap and the port *W* to the rearward end of the cylinder which will drive the piston forward. At the time that the edge *d* at the front end of the piston covers the port *e* of the passage *X*, the edge *f* of the neck *D* will have uncovered the port *g* of the live pressure fluid supply passage *T'* so that pressure fluid will flow around the neck *D* of the piston and through the port *h* in the side of the cylinder communicating with the passage *X* leading to the forward end of the valve so that the valve is then thrown rearwardly due to the differential areas of the valve.

As the valve is thrown rearwardly, live pressure fluid is supplied from the supply passage *R* in the handle around the neck *Z* of the valve and through the supply passage *V* to the front end of the cylinder. The piston however, has sufficient momentum to strike its blow upon the chisel shank *E* and commences its rearward motion before the pressure begins to build up in front of the piston to drive it rearwardly. This position of the parts is shown in Figure 8. The rearward motion of the piston is due both to rebound and to live pressure fluid admitted as described.

During the rearward travel of the piston when the edge *d* at the forward end of the piston uncovers the port *e* of the passage *X*

and the port *j* of the exhaust passage *U*, the edge *f* of the piston neck will have covered the ports *g* and *h* thus closing off the supply of live pressure fluid to the rearwardly acting pressure surface *c* of the valve and the forward end of the valve will thus be open to exhaust through the passage *X* and the exhaust passage *U*. At this time the live pressure fluid on the forwardly acting pressure surface *b* of the valve head or shoulder will throw the valve forwardly to the position indicated in Figure 7 and open the auxiliary exhaust for the front end of the cylinder through the passage *V* and over the rearward end of the valve to the main exhaust *S*. Before this occurs, however, the exhaust from the rearward end of the cylinder as the piston is traveling rearwardly passes out through the port *W* and through the ports *k* and *o* in the valve head and through the valve itself to the main exhaust *S*.

The pressure fluid trapped in the rearward end of the cylinder after the valve has shifted to its forward position but while the piston is moving rearwardly forms a cushion so that the piston is not stopped abruptly and due to its cushion reverses its movement without reversal of the movement of the valve. From this point the cycle is repeated.

The construction and arrangement of the valve and the operation of the piston are highly advantageous in this chipping hammer, since the forward end of the cylinder has a main exhaust through the passage *U* controlled by the piston, and also has an auxiliary exhaust through the passage *V* controlled by the valve so that ample exhaust ports are provided for the front end of the cylinder. The exhaust from the rear end of the cylinder is short and direct through the valve itself to the main exhaust *S*. By locating the main exhaust *S* directly rearward of the valve, the arrangement and location of the ports and passages in the valve box is facilitated. The valve is thrown and held in both directions by live pressure fluid and the action is positive and certain since the valve is preferably a differential valve. The valve is preferably coaxial with the piston which has the advantage that if the bolts of the handle should become loose and for any reason allow the piston to strike the forward cap of the valve box, no damage would be done to the valve bore in the valve box or to the valve itself, which might happen if the valve were located transversely in the valve box.

I claim:

1. A pneumatic hammer comprising a cylinder and reciprocating piston, a valve chest located at the rearward portion of the cylinder, a hollow pressure fluid controlled valve in said valve chest controlling the supply of

pressure fluid to both ends of the cylinder, an exhaust port in said valve chest rearward of the valve communicating with the forward end of the cylinder and controlled only by the piston, an auxiliary exhaust from the forward end of the cylinder controlled only by the valve and passing over one end of the valve to said exhaust port in the valve chest, a main exhaust from the rearward end of the cylinder controlled only by the valve for exhausting through the interior of the valve, and thence direct to said exhaust port in the valve chest, means for actuating and holding the valve forwardly by live pressure fluid, and means controlled by the piston for actuating and holding the valve rearwardly by live pressure fluid.

2. A pneumatic hammer comprising a cylinder, a reciprocating piston having a neck, a valve box at the rearward end of the cylinder, front and rear caps for said box, a hollow cylindrical valve in said box having its axis extending longitudinally of the cylinder, and formed with a forward enlarged head having a shoulder forming a forwardly

acting pressure surface and a neck intermediate the said head and the smaller open rearward end of the valve, passages controlled by the valve neck for supplying pressure fluid to both ends of the cylinder, a main exhaust rearwardly of the valve, a main free exhaust passage for the front end of the cylinder controlled only by the forward end of the piston and an auxiliary exhaust for said forward end of the cylinder controlled only by the rearward end of the valve and passing over said rearward valve end, exhaust means for the rearward end of the cylinder controlled by the valve and including means for exhausting through the interior of the valve, means for actuating and holding the valve forwardly by the pressure of live fluid on the shoulder of the valve head, and a passage controlled by the piston neck for supplying live pressure fluid to the forward surface of the valve head for actuating the valve rearwardly.

In testimony whereof I have signed this specification.

WILLIAM F. ZIMMERMANN.
